UNITED STATES PATENT OFFICE.

HOWARD M. NICHOLS, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

PROCESS OF AND APPARATUS FOR SPRINKLING ROADS.

1,137,077.

Specification of Letters Patent. Patented Apr. 27, 1915.

Application filed May 13, 1911. Serial No. 626,957.

To all whom it may concern:

Be it known that I, HOWARD M. NICHOLS, a citizen of the United States, residing at Philadelphia, in the county of Philadelphia and State of Pennsylvania, have invented certain new and useful Improvements in Processes of and Apparatus for Sprinkling Roads, of which the following is a specification.

This invention relates more particularly to the sprinkling of roads with the viscous liquids of an oily nature known as road oils, in order to effect a more permanent (or less temporary) laying of dust than results from sprinkling the roads with water. These road oils vary greatly in composition. Crude petroleum and undistilled residues of petroleum have been employed; also emulsions of such crude oils or residues with water and emulsifying agents, and other compositions are known.

The invention also extends in part to the sprinkling of roads with liquids (as water itself or saline solutions, for example) which are not of said oily and viscous nature.

Each of the improvements composing the invention is intended to be secured for all the uses to which it may with or without modification be adapted.

In the drawings: Figure 1 is a side elevation of a road sprinkling apparatus in accordance with the invention and in the form of a wheeled vehicle; Fig. 2 is a rear-end elevation of the same; Figs. 3 and 4 are side elevations on an enlarged scale of forms of nozzles embodying important features of the invention; and Figs. 5 and 6 are longitudinal sectional views of the respective nozzles shown in Figs. 3 and 4. Figs. 7 and 8 are views of said nozzles in longitudinal section in planes at right angles to those of Figs. 5 and 6, respectively.

Referring to the drawings, A is a vehicle body mounted in any suitable manner upon wheels B.

C is a receptacle for containing the liquid which is to be applied to the road. This receptacle is shown in the form of a cylindrical tank having a portion of the cylinder cut away at the front end to form a recess or reentrant portion for the driver's seat D, as will be understood from Fig. 1, the walls of the tank being suitably arranged to follow the outline of said recess. The receptacle C

is provided with a manhole or like filling opening indicated at c and having any suitable closure device.

The vehicle body A extends to the rear beyond the tank C and upon this extension is mounted an internal combustion engine E and a rotary pump F, the engine and pump shafts being in line with each other and detachably coupled by a sleeve coupling e, Fig. 2, the engine and pump being arranged with their shafts transversely of the vehicle body. 65

The engine is of the water cooled type and has a tank G for the circulating water, which tank is mounted on the vehicle body at one side of the receptacle C. Suitable pipes g g' extend from the water jacket of the engine to the tank G for circulation of the water by the aid of customary pumping means (not shown).

The water tank G is provided with a vent pipe g² in the form of a goose-neck whose outer end is open to the atmosphere. This pipe serves for the escape of any air or water vapor, thus avoiding pressure on the inside of the water tank. At G', Fig. 2, is shown a fuel tank, for gasoline or the like, 80 from which the engine is supplied.

From the bottom of the tank C a pipe H extends downward to a T connection H², which is provided with a plug at its lower end whereby the pipe H may be cleaned at 85 any time by the removal of said plug. From the T H² a pipe H³ extends to the rear of the vehicle, where it is provided with a hand valve H⁴ arranged to be coupled to a suction pipe or hose, not shown, when it is desired 90 to fill the tank by pumping from an outside source of supply. In said pipe are fittings H⁵, H⁶ and H⁷ for branch pipes H⁸, H⁹ and H¹⁰, respectively; and there is a hand valve H¹¹ intermediate the fittings H⁵ and H⁶. 95

The suction of the pump F is connected with pipe H¹⁰. The pump discharges through pipe K; with which the branch pipe H⁹ is connected at the top and the branch pipe H⁸ at the bottom. The pipe H⁸ leads to 100 a manifold or distributing pipe M (Fig. 2) extending transversely of the vehicle and supported by hangers M'.

At S is a step for an attendant workman to stand upon; so that he can attend to the 105 machinery while the vehicle is moving. The step S is upheld in front by hanger s and in the rear by the manifold M.

The branch pipe H^9 is provided with a relief valve K^2 . In order to indicate the pressure in the discharge pipe K , a suitable gage is provided as indicated at K^4 . The 5 relief valve is of the usual adjustable type so as to be set at the desired pressure. When this is exceeded, the relief valve will open and permit liquid to pass through the pipes H^9 and H^3 to the suction pipe H^{10} of the pump. In the branch pipe H^8 is a hand 10 valve L^8 .

The tank C may be filled through the manhole c , this method being employed when the tank is filled from a source of 15 supply located above the tank. When it becomes necessary to fill the tank by pumping from a source of supply below the tank, a suitable connection is made between the valve H^4 and such source of supply, as, for 20 example, by connecting a suction hose to the valve. The hand valve H^{11} is then closed to cut off the connection between the suction pipe H^{10} of the pump and the tank C . Also, the hand valve L^8 is opened to establish a 25 connection between the discharge pipe K of the pump and the pipe H at the bottom of the tank by way of the pipes H^8 , H^3 . The nozzles of the manifold pipe M are shut off, as more fully explained hereinafter, and the 30 engine may then be started to operate the pump. The liquid is then drawn by the pump through the suction hose (not shown), the open valve H^4 , the rear part of pipe H^3 and the suction pipe H^{10} and is 35 discharged through the pipe K , front parts of branch pipe H^8 , open valve L^8 , front part of pipe H^3 and pipe H into the tank C . When the tank C has been supplied with liquid, the valve H^4 is closed. Thereupon, 40 the valve H^{11} may be opened and the valve L^8 closed, thus putting the apparatus in condition for sprinkling. It will be noted that the relief valve K^2 and by-pass H^9 permit 45 this change to be made without stopping the engine, even though the nozzles on manifold M should be closed. This is not only of importance as avoiding the dangers of high pressure which might result in bursting 50 some of the pipes or connections if the valves were not manipulated in the right order, but is of considerable importance in connection with an internal combustion engine, since it allows the same to run under a constant load and thus permits a proper 55 timing of the spark, with consequent greater efficiency.

The manifold or distributing pipe M is connected to two sets of nozzles arranged in parallel rows transverse of the vehicle at 60 the rear of the same, the respective nozzles in one row alternating with respect to the nozzles of the other row. This arrangement allows the jets from the nozzles of different rows when of a laterally spreading 65 character to overlap in the direction of

travel. By shutting off the supply of liquid to the nozzles of one row, the road could still be fairly well (or even completely) covered by the discharges from the nozzles of the other row.

70

In the construction illustrated each of the nozzles N' of the forward set is carried by a pipe n' threaded into the manifold M , each pipe being provided with a hand valve n^3 and a stop-cock n^5 by either of which the 75 flow of liquid to the respective nozzle may be cut off. Each nozzle N^2 of the rear row is carried by a pipe n^2 which extends first rearward from the manifold M and then downward, this pipe n^2 being controlled by 80 a hand valve n^4 and a stop-cock n^6 .

The hand valves n^3 and n^4 form operable means for controlling the flow of liquid independently to the nozzles. The stop-cocks n^5 , n^6 , on the contrary, are connected by 85 levers n^7 with a rod n^8 , advantageously placed between the rows of nozzles and actuated by a hand lever or manipulator O ; which latter is fulcrumed at o and connected by a link o' with 90 rod n^8 . The connectedly operated stop-cocks enable the flow of the liquid onto the roadway to be applied and discontinued at the same instant across the roadway; so far as the hand valves may be open; and, 95 as these hand valves are independently operable, the flow from any desired nozzles can be stopped or regulated.

95

The nozzles employed are advantageously of a kind to deliver each a spreading jet; and they are arranged for the spreading to take place (in large part at least) transversely of the line of travel; so that each nozzle distributes its liquid over a comparatively wide strip; and the outer nozzle at each side of the vehicle is advantageously arranged to deliver its jet with the axis thereof inclined, as shown in Fig. 2, inward toward the middle of the vehicle. The advantage of this disposition is that the liquid can be more definitely confined to the strip which it is desired to sprinkle; since the outer edge of each outer jet being thus more nearly vertical than it would be were the jet's axis vertical or inclined outwardly reaches the ground after a shorter travel from the nozzle and is less apt to be deflected (as by the wind, for example). The nozzle is best arranged for the outer edge of its jet to be strictly or at least substantially vertical, as shown. The intermediate nozzles are best arranged to deliver jets with their axes in vertical planes parallel with the line of travel of the vehicle; and the jets in each row would best be in a vertical plane transverse of said line of travel, as shown in Figs. 1 and 2; but other arrangements are not excluded.

105

The nozzles shown are of a kind to deliver each its jet in the form of a fan-shaped sheet 130

110

115

120

125

which remains unbroken for some distance from the nozzle. As is known, such a sheet is of decreasing thickness as it recedes from the nozzle. If it is not interrupted, it eventually breaks up into a spray. It is advantageous that this breaking up should not occur far above the ground; as in that case the drops composing the spray are apt to be blown about and not land as desired. The 10 breaking up point of each fan-shaped sheet should not be nearer the nozzle than half the distance between the latter and the ground (and it is better not to be so near thereto). It might even strike the ground 15 in its unbroken condition; but in that case the liquid would not be so widely distributed. It is considered best for the nozzles to be about a foot or so from the ground at their lower ends and for the breaking up of 20 the fan-shaped sheets to occur within two or three inches of the ground. The pressure under which the liquid is supplied to the nozzles and other conditions would be adjusted to this object. The nozzles shown are 25 also of a kind to deliver the liquid through orifices whose corresponding dimension is at least double (and preferably more than double) the thickness of the jet issuing in sheet form therefrom; each jet being made 30 thin by the delivery of the issuing liquid in opposing currents, which are deflected and confined in order to form the jet. By use of this style of nozzle, the need of filtering the liquid is lessened or obviated, as the nozzle orifices can be made large enough (say a sixteenth of an inch, or preferably more) to allow the passage of particles likely to exist in road oils. Each nozzle may have a clear 35 opening of an eighth of an inch, or even more, in all directions and yet deliver a jet which is less than one eighth of an inch thick just beyond the lower end of the nozzle, where it may have a width say of twelve inches more or less. When it breaks into 40 drops the jet is greater in width and correspondingly thinner.

Each of the nozzles (Figs. 3 to 6) has a 45 passage p with parallel sides p' brought closer together than the remaining walls p'' ; so as to give said passage the general form of an elongated parallelogram in cross section; and this passage is closed at q on each side of the jet orifice r ; which extends a 50 short distance up one or both sides p' of the passage p . It is considered best for the closures q of the passage p to be curved in two 55 directions like the outer surface of a ring of circular cross section. The parallel sides of 60 said passage p are thus joined by surfaces (to wit, the inner surfaces of the closures q) which are deflected outwardly (as seen in 65 Figs. 5 and 6) in planes transverse to the flow of the fluid. The closures q turn the margins of the stream in passage p toward each other between the parallel sides of said

passage in planes parallel with said sides and thus form currents of oppositely flowing fluid which come into contact with each other in the middle of the jet orifice r in a plane transverse to their flow. This fluid is 70 confined on the side of the body of said passage for the full width of the contact of the currents on that side and is spread as a fan-shaped jet on other sides. By the outward deflection of the inner surfaces of the closures q the currents have convex outlines in planes transverse to their directions of flow. The passage p merges with the cylindrical portion p^3 of the nozzle. The top of each nozzle is screw threaded interiorly for engaging a pipe nipple between itself and one of the stop-cocks n^5 n^6 . Each nozzle is best made from a hollow cylinder closed at one end by a hemisphere. The cylinder for an 80 appropriate distance from and including the closed end is flattened as in Figs. 5 and 6; and the end is then notched to form the jet orifice r . Should it be desired for the axis of the issuing fan-shaped jet to coincide with the nozzle axis, the notch for the jet orifice is cut square across, as in Fig. 5; but if it is desired for the jet axis to be inclined, the notch is cut more on one side than on the other, as in Fig. 6. Nozzles of this latter form are designed to be placed at the sides 85 of the vehicle (extreme right and left hand nozzles of Fig. 2). On the vehicle the nozzles are arranged with the longer horizontal dimensions of passages p in the line of travel; the planes of Figs. 3 and 4 being 90 parallel with that of Fig. 1 and the planes of Figs. 5 and 6 parallel with that of Fig. 2.

The pressure developed by the pump F is 95 adjusted to discharge the road oil from the nozzles in such manner that the fan-shaped jets remain continuous, as at T , until they are within say two or three inches, more or less, of the ground and that they then break 100 up into separate drops or streams, as at T' . According to my experience, information 105 and belief, using nozzles as shown with jet orifices r an eighth by an eighth of an inch (that is, the notch in Fig. 3 being an eighth of an inch wide and the walls of passage p in Fig. 5 being separated by an eighth of an inch) located about 10 to 14 inches from 110 the ground, superatmospheric pressure of from 7 to 20 pounds as indicated on the gage K^4 (the valves in pipes leading thence to the nozzles N^1 N^2 being open to their full extent) would be required for different road 115 oils, according to their respective viscosities, the higher pressures being needed for the more viscous oils; but there may be road 120 oils which would require more pressure and some which would give the desired form of jet with less. Water would not need so high a pressure as 7 pounds to the square inch. Adjustment of the pressure by speeding the 125

motor E as indicated by the jets themselves will be a sufficient criterion. The relief valve K² can be set to open in case the normal pressure should be substantially exceeded. Road oil has been discharged onto the road at the rate of two gallons a minute through seven nozzles with jet orifices of the size mentioned (an average, that is, of $\frac{7}{8}$ of a gallon a minute). The amount per 10 square foot of road would, of course, depend upon the speed of travel.

I claim as my invention or discovery:

1. The process of producing a jet, by forcing fluid through a passage which has 15 an elongated cross section and sides that lie in parallel planes in the direction of such elongation, turning the margins of the flattened parallel sided stream so produced toward each other as oppositely flowing currents, and releasing the fluid at and for a distance on each side of the meeting plane of said currents across the full width of the latter and for a short distance back from their outermost edges, substantially as described.
2. The process of producing a jet, by forcing fluid through a passage which has 30 an elongated cross section and sides that lie in parallel planes in the direction of such elongation, turning the margins of the flattened parallel sided stream so produced toward each other as oppositely flowing currents, and releasing the fluid at and for a distance on each side of the meeting plane 35 of said currents across the full width of the latter and for a short distance back from their outermost edges at a jet orifice of approximately equal dimensions both longitudinally of and transversely to said currents, substantially as described.
3. A jet nozzle which is provided (1) with a passage therein adapted to convey fluid under pressure and having an elongated cross section and sides that lie in parallel planes in the direction of such elongation, (2) with means for turning the margins of the flattened parallel sided stream so produced toward each other as oppositely flowing currents, and (3) with a jet orifice 45 open at and for a distance on each side of the meeting plane of said currents across the full width of the latter and for a short distance back of their outermost edges, substantially as described.
4. A jet nozzle which is provided (1) with a passage therein adapted to convey fluid under pressure and having an elongated cross section and sides that lie in parallel planes in the direction of such elongation, (2) with means for turning the margins of the flattened parallel sided stream so produced toward each other as oppositely flowing currents, and (3) with a jet orifice of 50 approximately equal dimensions both longitudinally of and transversely to said currents, substantially as described.
5. A jet nozzle which is provided (1) with a passage therein adapted to convey fluid under pressure and having an elongated cross section and sides that lie in parallel planes in the direction of such elongation, (2) with means for turning the margins of the flattened parallel sided stream so produced toward each other as oppositely flowing currents, and (3) with a jet orifice of 55 approximately equal dimensions both longitudinally of and transversely to said currents, substantially as described.

rents open at and for a distance on each side of the meeting plane of said currents across the full width of the latter and for a short distance back of their outermost edges, substantially as described.

5. The process of producing a road sprinkling or other sprinkling jet, by forcing road oil or other liquid through a passage which has an elongated cross section, turning the margins of the flattened stream so produced toward each other as oppositely flowing currents, and releasing said liquid at and for a distance on each side of the meeting plane of said currents so as to produce a fan-shaped jet of the road oil or other liquid from a jet orifice whose corresponding dimension is great as compared with the thickness of said jet, substantially as described.

6. The process of producing a road sprinkling or other sprinkling jet, by forcing road oil or other liquid through a passage which has an elongated cross section and sides that lie in parallel planes in the direction of such elongation, turning the margins of the flattened parallel sided stream so produced toward each other as oppositely flowing currents, and releasing the road oil or other liquid at and for a distance on each side of the meeting plane of said currents across the full width of the latter and for a short distance back of their outermost edges, substantially as described.

7. The process of producing a road sprinkling or other sprinkling jet, by forcing road oil or other liquid through a passage which has an elongated cross section and sides that lie in parallel planes in the direction of such elongation, turning the margins of the flattened parallel sided stream so produced toward each other as oppositely flowing currents, and releasing the road oil or other liquid at an orifice of approximately equal dimensions both longitudinally of and transversely to said 105 oppositely flowing currents located at and for a distance on each side of the meeting plane of said currents and extending for a short distance back of their outermost edges, the pressure on said road oil or other liquid sufficing to deliver it as a continuous fan-shaped jet whose thickness at the end of the jet nozzle is less than half the corresponding dimension of said jet orifice, substantially as described.

8. The process of producing a road sprinkling or other sprinkling jet, by forcing road oil or other liquid through a sprinkler nozzle which delivers said road oil or other liquid as a continuous sheet of fan shape, and allowing the so delivered liquid free traverse for such distance that said sheet remains unbroken for more than half the same and then breaks into streams or drops, substantially as described.

9. The process of producing a road sprinkling or other sprinkling jet, by forcing road oil or other liquid through a passage which has an elongated cross section, turning the margins of the flattened stream so produced toward each other as oppositely flowing currents, releasing the road oil or other liquid at an orifice which is located at and for a distance on each side 10 of the meeting plane of said currents and allows the said liquid to issue as a continuous sheet of fan shape spreading transversely to said currents, and allowing the so issuing liquid free traverse for such distance that said sheet remains unbroken for 15 more than half the same and then breaks into streams or drops, substantially as described.

10. The process of producing a road 20 sprinkling or other sprinkling jet, by forcing road oil or other liquid through a passage which has an elongated cross section and sides that lie in parallel planes in the direction of such elongation, turning the 25 margins of the flattened parallel sided stream so produced toward each other as oppositely flowing currents, releasing the road oil or other liquid at an orifice of approximately equal dimensions both longitudinally of and transversely to said oppositely flowing currents located at and for 30 a distance on each side of the meeting plane of said currents and extending for a short distance back of their outermost edges, the 35 pressure on said road oil or other liquid sufficing to deliver it as a continuous sheet of fan shape spreading transversely to said oppositely flowing currents and having a thickness at the jet nozzle of less than half 40 the corresponding dimension of said orifice, and allowing the so issuing liquid free traverse for such distance that said sheet remains unbroken for more than half the same and then breaks into streams or drops, sub- 45 stantially as described.

11. A sprinkler nozzle, which is provided 50 (1) with a passage therein adapted to convey road oil or other liquid under pressure and having an elongated cross section so as to give a flattened form to the stream of passing liquid, (2) with means for turning the margins of such flattened stream toward each other as oppositely flowing currents, and (3) with a jet orifice located at and for 55 a distance on each side of the meeting plane of said currents, so as to produce a fan-shaped jet of said road oil or other liquid from a jet orifice whose corresponding dimension is great as compared with the thickness of said jet, substantially as described.

12. A sprinkler nozzle, which is provided 60 (1) with a passage therein adapted to convey road oil or other liquid under pressure and having an elongated cross section and sides that lie in parallel planes in the direc-

tion of such elongation, (2) with means for turning the margins of the flattened parallel sided stream so produced toward each other as oppositely flowing currents, and (3) with a jet orifice located at and for a distance on 70 each side of the meeting plane of said currents and extending across the full width of said currents and for a short distance back of their outermost edges, substantially as described.

13. A sprinkler nozzle, which is provided 75 (1) with a passage therein adapted to convey road oil or other liquid under pressure and having an elongated cross section and sides that lie in parallel planes in the direction of such elongation, (2) with means for turning the margins of the flattened parallel sided stream so produced toward each other as oppositely flowing currents, and (3) with a jet orifice of approximately equal dimensions both longitudinally of and transverse to said currents located at and for a distance on each side of the meeting plane of 80 said currents and extending for a short distance back of their outermost edges, the said nozzle operating to deliver road oil or other liquid under appropriate pressure as a continuous fanshaped jet whose thickness at the end of said nozzle is less than half the corresponding dimension of said jet orifice, sub- 90 stantially as described.

14. The process of sprinkling a road or other surface, consisting in applying thereto 100 fan-shaped jets of road oil or other liquid of the special character of those which are produced under pressure by turning the margins of flattened streams of said liquid toward each other and releasing the liquid of each stream the full width of the oppositely flowing currents which result from 105 said turning toward each other of the streams' margins, substantially as described.

15. The process of sprinkling a road or other surface, consisting in applying thereto 110 fan-shaped jets of road oil or other liquid of the special character of those which are produced by forcing a stream of the sprinkling liquid through a parallel sided passage and turning the margins of said stream toward each other between the parallel sides 115 of said passage in planes parallel with said sides and releasing the fluid on the sides away from the body of said passage, substantially as described.

16. Apparatus for sprinkling a road or 120 other surface with road oil or other liquid, which apparatus consists of means for producing fan-shaped jets of said liquid under pressure by turning the margins of flattened streams of said liquid toward each other and 125 releasing the liquid of each stream the full width of the oppositely flowing currents which result from said turning toward each other of the streams' margins, in combination with appliances for supplying the sprinkling 130

liquid under pressure to said jet producing means, and means for applying said fan-shaped jets to the surface to be sprinkled, substantially as described.

- 5 17. Apparatus for sprinkling a road or other surface with road oil or other liquid, which apparatus consists of jet nozzles and appliances for supplying the sprinkling liquid thereto under pressure, and the jet 10 nozzles of which have each of them, a parallel sided passage therein, with means for turning the margins of said stream toward each other between the parallel sides of said passage in planes parallel with said sides so 15 as to bring portions of said stream into contact with each other as oppositely flowing currents, and are arranged to confine the fluid on the side next the body of said passage and to release it on other sides, so that 20 it may escape as a fan-shaped jet, substantially as described.

18. The process of sprinkling a road or other surface, by carrying over said surface fan-shaped jets of road oil or other liquid 25 which issue as continuous sheets and are arranged across the line of travel with the jets spreading transversely to said line and which include at one end at least of the row 30 of jets a fan-shaped jet whose axis is inclined inward at such an angle as to bring the outer edge of the jet into a vertical position, thus giving a better defined edge to the area of sprinkling in view of the greater stability of said vertical edge as compared 35 with one which is inclined, substantially as described.

19. Apparatus adapted to be carried over a road or other surface and having sprinkler nozzles which are arranged across such line 40 of travel and operate to deliver road oil or other sprinkling liquid in fan-shaped jets that issue as continuous sheets transverse to the line of travel and include a fan-shaped jet of such character at one end at least of 45 the row of jets with its axis inclined inward at such an angle as to bring its outer edge into a vertical position, thus giving a better defined edge to the area of sprinkling in view of the greater stability of said vertical 50 edge as compared with one which is inclined, substantially as described.

20. The process of sprinkling a road or other surface, consisting in carrying over such surface fan-shaped jets of road oil or 55 other liquid directed toward said surface, which jets issue in the form of continuous sheets under such pressure that said sheets remain unbroken for more than half the distance between the jet orifices and said surface, substantially as described.

21. The process of sprinkling a road or other surface, consisting in carrying over such surface fan-shaped jets of road oil or 60 other liquid directed toward said surface, which jets issue in the form of continuous

sheets under such pressure that said sheets remain unbroken for more than half the distance between the jet orifices and said surface, but break into streams or drops before reaching said surface, substantially as described. 70

22. Apparatus for sprinkling a road or other surface with road oil or other liquid, consisting of jet nozzles of a kind to deliver fan-shaped jets which issue in the form of 75 continuous sheets when the road oil or other liquid is supplied thereto under suitable pressure, means for supporting said nozzles in positions in which they are directed toward the surface to be sprinkled and are 80 located in suitable proximity thereto and for carrying said nozzles over said surface, and means for supplying road oil or other liquid to said nozzles under pressure appropriate for producing jets which remain in the form 85 of unbroken sheets for more than half the distance between the jet orifices and said surface, substantially as described.

23. Apparatus for sprinkling a road or other surface with road oil or other liquid, 90 consisting of jet nozzles of a kind to deliver fan-shaped jets which issue in the form of continuous sheets when the road oil or other liquid is supplied thereto under suitable pressure, means for supporting said nozzles 95 in positions in which they are directed toward the surface to be sprinkled and are located in suitable proximity thereto and for carrying said nozzles over said surface, and means for supplying road oil or other liquid 100 to said nozzles under pressure appropriate for producing jets which remain in the form of unbroken sheets for more than half the distance between the jet orifices and said surface, but break into streams or drops 105 before reaching said surface, substantially as described.

24. The process of sprinkling a road or other surface, consisting in discharging upon the road or other surface road oil or other 110 liquid in the form of fan-shaped jets which issue as sheets from jet orifices whose dimension in the direction corresponding with the thickness of the issuing sheets is not less than twice such thickness immediately outside of the jet orifices, each sheet being formed by oppositely flowing currents and issuing in the meeting plane of said currents, substantially as described. 115

25. The process of sprinkling a road or other surface, consisting in discharging upon the road or other surface road oil or other liquid in the form of fan-shaped jets which issue as sheets from jet orifices which in the direction corresponding with the thickness 120 of said sheets is not less than about a sixteenth of an inch across, each sheet being reduced in thickness at the end of the corresponding jet nozzle to less than half of such dimension by the interference of opposing 125 130

currents and issuing in the meeting plane of said currents, substantially as described.

26. The process of sprinkling a road or other surface, consisting in discharging road oil or other liquid upon the same in the form of fan-shaped jets produced under pressure by currents of said liquid oppositely flowing into contact with each other and escaping for each jet by an orifice whose dimension in the direction of flow of said currents approximates its dimension widthwise of said currents and is not less than about a sixteenth of an inch as a minimum, substantially as described.

27. Apparatus for sprinkling a road or other surface with road oil or other liquid, consisting of jet nozzles of a kind to deliver fan-shaped jets which issue as sheets from the jet orifices of said nozzles, and are made thinner than the corresponding dimension of said orifices by the interference of opposing currents of the liquid that meet within the nozzles midway of the respective jet orifices, means for supporting said nozzles in positions in which they are directed toward the surface to be sprinkled and are located in suitable proximity thereto and for carrying said nozzles over said surface, and means for supplying road oil or other liquid to said nozzles under pressure appropriate for producing jets whose thickness immediately outside of said orifices is not more than half the corresponding dimension of the latter, the jet nozzles being adapted for production of such jets when supplied with road oil or other liquid under appropriate pressure, substantially as described.

28. Apparatus for sprinkling a road or other surface with road oil or other liquid, consisting of jet nozzles of a kind to deliver fan-shaped jets which issue as sheets from the jet orifices of said nozzles, and are made thinner than the corresponding dimension of said orifices by the interference of opposing currents of the liquid that meet within the nozzles midway of the respective jet orifices, means for supporting said nozzles in positions in which they are directed toward the surface to be sprinkled and are located in suitable proximity thereto and for carrying said nozzles over said surface, and means for supplying road oil or other liquid to said nozzles under pressure appropriate for producing jets whose thickness immediately outside of said orifices is not more than half the corresponding dimension of the latter, the jet nozzles being adapted for production of such jets when supplied with road oil or other liquid under appropriate pressure, and having jet orifices of not less than about a sixteenth of an inch across in the direction corresponding with the thickness

of the issuing sheets, substantially as described.

29. Apparatus for sprinkling a road or other surface with road oil or other liquid, consisting of means for discharging said liquid upon the surface to be sprinkled in the form of fan-shaped jets produced under pressure by currents of said liquid oppositely flowing into contact with each other and escaping for each jet by an orifice whose dimension in the direction of flow of said currents approximates its dimension widthwise of said currents and is not less than about a sixteenth of an inch as a minimum, in combination with appliances for supplying the liquid to said liquid discharging means, substantially as described.

30. Apparatus for sprinkling a road or other surface with road oil or other liquid, having two rows of jet nozzles, a stop-cock for each nozzle, a single manipulator for the stop-cocks of both rows, a reciprocating rod located in the space between said rows and mechanically connected with the stop-cocks of both rows, and a mechanical connection between said manipulator and said rod for shifting the latter back and forth, substantially as described.

31. Apparatus for sprinkling a road or other surface with road oil or other liquid, consisting of a supply tank, sprinkling appliances, a pump, pipe connections between the supply tank and the pump inlet, pipe connections between the pump outlet and said sprinkling appliances, a valved inlet and coupling appertaining to the first mentioned pipe connections, means for closing at will the communication between the pump and said sprinkling appliances, a pipe with a stop valve therein communicating with the second mentioned pipe connections between the pump and said means and also communicating with the first mentioned pipe connections, an additional pipe provided with a relief valve therein and communicating with the second mentioned pipe connections between the pump and said means and with the first mentioned pipe connections, and a valve in the first mentioned pipe connections between the respective junctions of said pipe having a stop valve therein and said additional pipe therewith and also between the pump and the junction of said pipe having a stop valve therein with the first mentioned pipe connections, substantially as described.

In testimony whereof I affix my signature in presence of two witnesses.

HOWARD M. NICHOLS.
